(57) **CLAIM**

The ornamental design for a door for a vehicle cab, as shown.

DESCRIPTION

FIG. 1 is a front perspective view of a door for a vehicle cab embodying my new design;

FIG. 2 is a top plan view thereof;

FIG. 3 is a front elevational view thereof;

FIG. 4 is a side elevational view thereof as viewed from a first side;

FIG. 5 is a side elevational view from a side opposite that shown on FIG. 4;

FIG. 6 is a rear elevational view thereof; and,

FIG. 7 is a bottom plan view thereof, the broken line representation form no part of the design.
